UNITED STATES PATENT OFFICE

2,327,031

STEM AND MOUNT CONSTRUCTION

Charles L. Fantur, East Cleveland, Ohio, assignor
to General Electric Company, a corporation of
New York

Application August 10, 1942, Serial No. 454,339

3 Claims. (Cl. 176—35)

This invention relates to filament mounts suitable for incandescent lamps or other electrical devices, and especially for lamps in which a relatively concentrated light source is desirable, and a relatively high wattage at low voltage, as in the case of certain lamps for producing a definite light beam, such as automobile spotlight lamps, for example. One important aim of the invention is to obviate or minimize deterioration or failure of the inlead seal of such a lamp, owing to the heat to which the seal is subjected because of the high temperature of the concentrated filament and the high amperage current carried by the leads. Other features and advantages of the invention will become apparent from the description of a species or form of embodiment of the invention, and from the drawing.

The drawing is a tilted or perspective view of a lamp conveniently embodying the invention, a portion of the outer lamp envelope being broken away.

The drawing illustrates an incandescent lamp with an ordinary type of bulb or envelope 10 that includes an inward extending hollow stem 11 with a seal 12 at its inner end. The lamp may be mounted in an ordinary base 13, here shown as of bayonet type. Besides the stem 11, the lamp mount may include the usual exhaust tube 14, inside the stem, fused and opening laterally through the stem wall in or just below the seal 12, and itself sealed or tipped off at 15. The current leads 16, 17 that connect to the shell and center contacts 18, 19 of the base 13 are sealed through the stem seal 12 and extend therefrom inward into the interior of the bulb 10 to supply energy to the incandescent filament 20, which may be a coil of refractory metal, such as tungsten, and is shown bent into a hairpin shape. The lamp bulb 10 may have the usual gas filling (such as 88 per cent argon and 12 per cent nitrogen), at an absolute pressure of 600 mm. of mercury at ordinary atmospheric temperature.

As here shown, each of the inleads 16, 17 is composite, consisting of multiple wire strands 21, 21 extending separately through the stem seal 12, and spaced well apart therein. Thus at the seal 12 the individual wires 21 lie at the corners of a rectangle which is very nearly a square. Outside the seal 12, the wires 21, 21 of each lead 16, 17 may be twisted together as shown, to facilitate handling them and connecting them to the base contacts 18, 19. Inside the seal 12, the two wires 21, 21 of the set forming each lead 15, 16 are slightly offset toward one another in their common plane at 22, 22, and are also both bent (be-

low their offsets) to slope and diverge outward away from the other lead. At their upper ends, the wires 21, 21 of each lead 16 or 17 are connected or attached to a stout spud 25, which as here shown consists of a single stout wire laterally welded to the wires 21, 21, instead of being formed by twisting the wires 21, 21 together. As shown, each spud 25 lies between its wires 21, 21, and these wires are welded to opposite sides of the spud directly opposite one another, making a strong, rigid structure not easily bent or twisted out of shape. The coiled filament 20 has its ends laterally welded to the adjacent ends of the spuds 25, 25, as shown, at the same sides thereof. The spuds 25, 25 extend laterally from the leads 16, 17 and are preferably in axial alignment with one another. With the spuds 25, 25 extending inward toward one another as shown, their inner ends lie close together; but the hairpin arrangement of the filament 20 nevertheless allows it to be made of ample length.

Besides the structural advantages already referred to, the construction described offers important advantages in increased average lamp life, because of the better performance at the seal 12. With the usual two-wire construction, lamps in which relatively high wattage is developed in a very compact filament arrangement and in a small bulb show many failures due to cracking or other "airing up" at the seal 12. This is especially true for certain lamps of low voltage and high current, such as a 100 C. P. 5.5. v. lamp in a G16½ bulb operating on a current of 12 amperes. As well understood commercially, a G16½ bulb is a spherical or globular bulb 2½ inches in diameter, a small space and wall surface for so much energy as 66 watts. With the multiple wire lead construction, both the heat conducted along the leads 16, 17 from the filament and that developed in the leads themselves is more evenly distributed in the seal 12, and fewer seal cracks or other early lamp failures occur. Moreover, the large surface of the large spuds 25, 25 and the spread of the four wires 21 inside the bulb 10 allows freer dissipation of heat by radiation from the leads before it reaches the seal. Being each smaller than a single wire of current-carrying capacity equivalent to two of them, the wires 21 are easy to bend after sealing in, so that fewer seals are broken or cracked in bending the wires for the purpose of completing the mount. For a 100 C. P. projector lamp such as above referred to, the inleads 21 may be of 30 mil nickel and the spuds 25 of 60 mil nickel. This

gives much better results than the ordinary construction with but two inleads of 50 mil nickel, or larger.

What I claim as new and desire to secure by Letters Patent of the United States is:

1. A stem and filament mount construction comprising a stem with sealed end, pairs of multiple leads sealed through the sealed stem end and extending therefrom, spuds attached to the leads of respective pairs and extending therefrom toward one another, and a coiled filament connected between said spuds.

2. A stem and filament mount construction comprising a stem with sealed end, pairs of multiple leads sealed through the sealed stem

end and extending therefrom, spuds between the leads of the respective pairs welded thereto and extending laterally therefrom, and a coiled hairpin filament connected between said spuds.

5 3. A stem and filament mount construction comprising a stem with sealed end, pairs of multiple leads sealed through the sealed stem end and extending therefrom, the several leads traversing the stem seal in relative positions corresponding to the corners of a rectangle, spuds attached to the leads of respective pairs and extending therefrom, and a coiled filament connected between said spuds.
